US00D639450S

(12) **United States Design Patent**
Vogler et al.

(10) **Patent No.:** **US D639,450 S**
(45) **Date of Patent:** ** Jun. 7, 2011

(54) **STORAGE ENCLOSURE**

(75) Inventors: **Michael R. Vogler**, Oswego, IL (US);
Michael Uffner, Naperville, IL (US)

(73) Assignee: **Suncast Technologies, LLC**, Palm
Beach Gardens, FL (US)

(**) Term: **14 Years**

(21) Appl. No.: **29/350,635**

(22) Filed: **Nov. 20, 2009**

(51) LOC (9) Cl. **25-01**

(52) U.S. Cl. **D25/33**

(58) **Field of Classification Search** D25/1-33;
52/79.4, 81.5, 236.1, 274, 74, 71, 245-246,
52/82, 79.1, 79.5, 90.1, 64

See application file for complete search history.

(57) **CLAIM**

The ornamental design for a storage enclosure, as shown and described.

DESCRIPTION

FIG. 1 is a top right perspective view of the storage enclosure of the instant invention;

FIG. 2 is a front view thereof;

FIG. 3 is a right side view thereof;

FIG. 4 is a left side view thereof; and,

FIG. 5 is a top view thereof.

The portions of the figures illustrated in broken lines are for illustrative purposes only and form no part of the claimed design.
